UNITED STATES PATENT OFFICE.

JOHN HENRY HUNTER, OF WEBB CITY, ARKANSAS.

CULTIVATOR.

SPECIFICATION forming part of Letters Patent No. 470,574, dated March 8, 1892.

Application filed July 11, 1891. Serial No. 399,193. (No model.)

To all whom it may concern:

Be it known that I, JOHN HENRY HUNTER, a citizen of the United States, residing at Webb City, in the county of Franklin and State of 5 Arkansas, have invented certain new and useful Improvements in Cotton-Cultivators; and I do hereby declare the following to be a full, clear, and exact description of the invention, such as will enable others skilled in the art to which it appertains to make and use the same.

My invention consists in a new and improved cotton-cultivator, in which the scraper-beam is so constructed and attached that it 15 can be readily removed when desired, to convert the cultivator into an ordinary double-shovel plow, my invention being provided with means for adjusting the distances between the several beams or standards with 20 peculiarly-constructed cutting-blades and with other novel features, all of which will be hereinafter fully described and claimed.

Referring to the accompanying drawings, Figure 1 is a perspective view of my new and 25 improved cotton-cultivator. Fig. 2 illustrates in detail the removable scraper-beam. Fig. 3 illustrates in detail one of the cutting-blades.

Referring to the several parts by their designating numerals, 1 indicates the main plow-beam, near the forward end of which is hinged 30 the front end of the auxiliary beam 2, which is shorter than the main beam, as shown. The handles 3 are secured and braced to the beams 1 2, as shown.

35 4 indicates the removable scraper-beam, on the lower rear end of which is mounted the scraping-blade 5. The forward end of this beam is curved in the same horizontal plane at nearly a right angle to the body of the beam 40 and is then curved around to form an open loop or U-shaped end 6. The forward end of the straight part of the scraping-beam is formed with the aperture 7, and the extremity of the curved end is formed with the aperture 8, the 45 two apertures registering with each other, and a retaining-bolt 9 passes through these apertures.

To place the scraper attachment in its operative position, it is only necessary to 50 move the bolt 9 and slip the curved front end 6 of the scraper-beam over the forward portion of the main beam 1 and replace the re-

taining-bolt 9 through the apertures 7 8. A threaded rod 10 passes through transverse apertures in the beams 1, 2, and 4, and nuts 55 11 are fitted upon it, one pair on each side of the three beams. It will now be seen that by turning these adjusting-nuts 11 the distance between the main beam and the auxiliary beam 2 and the distance between the 60 scraper-beam and the beam 2 can be readily adjusted to the exact width required. The scraper-beam, as shown, is shorter than the beam 2 near which it is placed. The removable beam 4, as before stated, carries the 65 scraping-blade.

A small plow-blade 2^a is mounted on the middle beam 2, while at the rear of the beam 1 is mounted the blade 12, which is shown in the drawings in Fig. 3, and which I shall now 70 describe. This blade 12 is formed of the two narrow curved sections 12^a 12^b, which merge at their forward ends into a beveled and sharpened point. This blade is adjustably secured to the beam 1 by the clamping- 75 plates 13, so that it can be adjusted up or down, as desired, to regulate the depth of its cut, and it will be seen that while this blade will cut readily through the ground its open character will enable the earth to pass through 80 it between the two side sections of the blade, making a much cleaner cut than is possible with the ordinary solid blade. By raising the blade 12 slightly the lower pointed end of the depending tooth 1^a, which is connected 85 to the beam 1, will project down below the blade, so as to act as a subsoiler.

From the foregoing description, taken in connection with the accompanying drawings, the construction, operation, and advantages 90 of my new and improved cotton-cultivator will be readily understood. The scraper-beam can be readily removed when desired, leaving the plow arranged to operate as a double shovel. By closing the beams 1 and 95 2 together when the scraper-beam 4 has been removed and using only one blade the cultivator can be used as a one-horse scraper.

Having thus described my invention, what I claim, and desire to secure by Letters Patent, is—

1. As an improvement in cultivators, the combination, with the beams 1 and 2, carrying their respective blades, of the remov-

able beam 4, provided with the scraper-blade, formed with the angular U-shaped forward end having the opposite apertures 7 8, and provided with a removable retaining-bolt 9, 5 substantially as set forth.

2. In a cultivator, the combination, with a beam and a cutting-tooth connected to and depending from said beam, of the open blade comprising the converging sections merged 10 into a point at their lower ends and straddling the lower portion of the tooth and a suitable means for adjustably connecting said blade to the beam, substantially as and for the purpose set forth.
- 15 3. In a cultivator substantially as described, the combination, with the main beam, the

auxiliary beam flexibly connected at its forward end to said main beam, and the removable beam having the angular U-shaped loop at its forward end straddling the main beam 20 and connected thereto, of the transverse threaded rod taking through the respective beams and nuts mounted on said rod on both sides of the said beams, substantially as set forth.

25 In testimony whereof I affix my signature in presence of two witnesses.

JOHN HENRY HUNTER.
